(57) **CLAIM**

I claim the ornamental design for a case for tablet PC, as shown.

DESCRIPTION

FIG. 1 is a front/right-side/top perspective view of a case for tablet PC showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof;

FIG. 7 is a bottom-side elevational view thereof; and,

FIG. 8 is a rear perspective view show in an environment of use, the broken lines forming no part of the claim.
